(57) **CLAIM**

The ornamental design for a female toy figure, as shown and described.

DESCRIPTION

FIG. 1 is a front view of a female toy figure showing my new design;

FIG. 2 is a rear view of the female toy figure;

FIG. 3 is a right side view of the female toy figure, a left side view being a mirror image thereof;

FIG. 4 is a top view of the female toy figure;

FIG. 5 is a bottom view of the female toy figure; and,

FIG. 6 is a top front side perspective view of the female toy figure.

The broken lines in FIG. 5 define borders inside which forms no part of the claimed design.
